UNITED STATES PATENT OFFICE

2,507,462

ELECTRIC PLUG

Ira G. Sellers, San Diego, Calif.

Application October 23, 1947, Serial No. 781,617

1 Claim. (Cl. 173—361)

1

This invention relates to new and useful improvements in electric plugs and the primary object of the present invention is to provide a plug so designed as to permit the same to be quickly and readily applied to extension cords or the like in a simple and practical manner.

Another important object of the present invention is to provide an electric plug including novel and improved means for retaining conductive wires in a tightly adjusted position relative to the plug.

A further object of the present invention is to provide contact fingers and novel and improved means for operatively connecting the fingers in contact with the ends of conductive wires without the necessity of having to remove any insulation from the wires.

A still further aim of the present invention is to provide an electric plug that is simple and practical in construction, strong and reliable in use, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view of the present electric plug, and showing the same applied to a section of an insulated conductive cord;

Figure 2 is a similar view of Figure 1, and with parts of the present invention being broken away and shown in section;

Figure 3 is a perspective view of the present electric plug, and showing the conductive wires, contact fingers and wedge pins removed therefrom; and,

Figure 4 is a group perspective view of the contact fingers and the means for connecting the same to the ends of a conductive wire.

Referring now to the drawings in detail, wherein for the purpose of illustration there is disclosed a preferred embodiment of the present invention, the numeral 10 represents a cylindrical body of insulating material that is provided with an enlarged preferably frusto conical head 12 at one end. The body 10 has a longitudinal bore 14 that communicates with a substantially frusto conical chamber or recess 16 provided in the head 12. The chamber 16 terminates in an annular recessed portion 18 having its end wall 20 spaced

parallel to the substantially flat annular, outer face 22 of the head 12.

An aperture or pin seat 24 centrally located in the outer face 22 of the head 12, communicates with the recessed portion 18 and frictionally engages a cylindrical wedge pin 26 having its inner end 28 tapered to extend between a pair of insulated conductive wires 30 and 32 that are inserted through bore 14 and into chamber 16 and recess 18, and the tapered end 28 of the pin forces the conductive wires to bear against the inclined inner walls of chamber 16 adjacent the bore 14, as shown best in Figure 2 of the drawings.

15 The numeral 34 represents conductive caps that are provided with bevelled seats 36 for frictionally engaging the terminals of wires 30 and 32. Internally threaded apertures 38 are provided in these caps and communicate with seats 36. These apertures 38 adjustably engage the externally threaded portion 40 of contact fingers 42.

In practical use of the device, the wires 30 and 32 are extended through bore 14, chamber 16 and outwardly through aperture 24, so that the

25 caps 34 may frictionally engage the terminals of the wires 30 and 32. The threaded portions 40 of the contact fingers 42 are then adjusted in apertures 38, so that the pointed extremities 44 at one terminal of said contact fingers will engage the

30 core of the wires 30 and 32 to conduct a source of electricity from the wires to the contact fingers 42, as shown best in Figure 3 of the drawings. The portion of the contact fingers adjacent the threaded portions 40, are then frictionally

35 fitted into slits 46 that connect the apertures 24 to contact finger seats 48 provided in the face 22 of head 12, that communicate with chamber 16, so that the contact fingers will project outwardly from the head in spaced parallelism relative to each other. The wedge pin 26 is then frictionally

40 driven into the aperture 24, so that its tapered end 28 will force the wires 30 and 32 to bear against the inner wall of chamber 16 adjacent bore 14, thus retaining the wires fixedly secured in the electric plug thus described.

45 In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a 50 preferred embodiment of the invention the same

is susceptible to certain changes fully comprehended by the spirit of the invention as herein described and the scope of the appended claim.

Having described the invention what is claimed as new is:

An electric plug comprising an insulated resilient body having an axial bore, said bore having inner and outer end portions, a recess provided in said body and forming an enlargement of said bore, said body having an end wall in which the inner end portion of said bore is provided, a pair of openings in the end wall spaced from each other and the inner end portion of said bore, slits provided in said end wall and connecting the pair of openings with the inner end portion of said bore, a pair of conductive wires having inner end portions extending through the outer end portion of said bore and into said recess, the inner end portions of said wires having tips, caps fitted on the tips of said wires and disposed beneath the end wall of said body, said caps having internally threaded apertures, a pair of contact fingers having threaded end portions receivably engaging the threaded apertures, pointed elements projecting from the threaded end portions of said contact fingers and contacting the tips of said wires, and a cylindrical wedge frictionally fitted in the inner end portion of said bore and having a tapered end forcing the wires against the inner wall of said

recess, said wedge also retaining said caps spaced from each other, said wedge adapted to ride against said caps for forcing the fingers from the inner end portion of the bore laterally through said slits and into said pair of openings during assembly.
